UNITED STATES PATENT OFFICE.

FRANK E. WILLIAMS, OF LOS ANGELES, CALIFORNIA.

DESIGN FOR A SET OF PLAYING-CARDS.

50,003.

Specification for Design.

Patented Dec. 5, 1916.

Application filed September 7, 1915. Serial No. 49,411. Term of patent 14 years.

To all whom it may concern:

Be it known that I, FRANK E. WILLIAMS, a citizen of the United States, residing at Los Angeles, in the county of Los Angeles and State of California, have invented a new, original, and ornamental Design for a Set of Playing-Cards, of which the following is a specification, reference being had to the accompanying drawings, forming part thereof.

Copies of this patent may be obtained for five cents each, by addressing the "Commissioner of Patents, Washington, D. C."

The Figures 1 to 15 illustrate in plan view a set of playing cards showing my new design.

I claim:

The ornamental design for a set of playing cards, as shown.

FRANK E. WILLIAMS.
